UNITED STATES PATENT OFFICE.

JOSIAH S. ANDREWS, OF BUFFALO, NEW YORK.

VEHICLE JACK.

Application filed March 10, 1920. Serial No. 364,642.

To all whom it may concern:

Be it known that I, JOSIAH S. ANDREWS, a citizen of the United States, residing at Buffalo, in the county of Erie and State of New York, have invented certain new and useful Improvements in Vehicle Jacks, of which the following is a specification.

My invention relates to a lifting jack, and more particularly to a jack adapted for vehicles, especially automobiles.

The primary object of my invention is to provide a simple, powerful and inexpensive jack of this kind whereby a portion or one end of a vehicle may be lifted by a single action of the actuating element of the jack, and in which provision is made for retaining the vehicle in elevated position.

A further object of my invention is the provision of a jack of this kind which can, in the main, be constructed of waste material, the whole being formed of a plurality of parts assembled and fastened together in a simple and inexpensive manner.

A still further object of my invention is to provide a jack of this character, which is almost entirely constructed of wood and which is adjustable so that it is adapted for use on vehicles having their axles at different distances from the floor or ground.

A still further object of my invention is to provide a single-acting jack for this purpose having a comparatively big leverage, and which is so constructed that the supporting portion and the actuating portion can be quickly separated from each other so that the jack can be conveniently stored in the vehicle.

With these and other objects in view, the invention consists in the novel features of construction, and in the arrangement and combination of parts to be hereinafter described and more particularly pointed out in the subjoined claims.

In the drawings:

Fig. 1 is a perspective view of my improved vehicle-jack.

Fig. 2 is a front elevation of the same.

Fig. 3 is a vertical longitudinal section through the front end of the jack, part of the actuating element being shown in elevation.

The device comprises essentially a support 3, and actuating mechanism 4 including a retaining element 5. The support 3 is preferably constructed of wood, in the main, and it comprises a flat base 6, an up-

right 7 formed of two flat side members 8 spaced apart by a stepped spacing block 9, the block having at least two steps or abutments 10 formed thereon. The extension 11 of said block, so called by reason of its approaching the upper ends of the side members 8 closer than the abutments 10, serves to render the support more rigid than if the upper abutment 10 were continued to the rear edge of the support; and in some cases the upper surface of this upward extension may also serve as an abutment.

The upright 7 is fastened to the base by means of bolts 12 extending through said base into the spacing block 9, and the side members 8 are fastened to said spacing block by means of through bolts 13. The side members are inclined at their front edges from a point intermediate their ends to their upper edges. Each side member 8 of the upright or support has a metallic strip 14 applied to its outer surface, with one edge thereof flush with the inclined edge of the side member, said metallic strip 14 extending along a portion of the vertical front edge of the side member and along the upper edge thereof, as best shown in Fig. 2.

At the upper edges of the side members, semi-cylindrical bearing notches 15 are formed, these notches being also formed through the metallic strips 14, and along the inclined edges of the side members similar bearing notches 16 are formed, the notches 15 being alined with each other while the notches 16 are also alined, and while I have shown a single pair of notches 16 at the inclined edges of the side members, it is apparent additional alined notches may be formed in said edges.

The space between the side members not occupied by the spacing block provides the necessary clearance for the actuating mechanism 5, which comprises a comparatively long actuating lever 17, preferably formed rectangular in cross section, except at its rear end where it is formed cylindrical for conveniently grasping the same. The width of this actuating lever is such that it fits freely between the side members of the upright or support so that it can be easily positioned in place and as readily removed from between said side members.

Projecting from opposite sides of said lever are bearing pivots 18, these being preferably formed by inserting a short length of

- pipe through a circular opening formed transversely in said lever, opposite ends of the pipe extending beyond the side faces of said lever. With a view of preventing rotation of said pivots and also lengthwise movement thereof, a bolt 19 is passed through the lever and pipe at right angles to the latter, a nut 20 being applied to said bolt to retain the latter within said lever.
- 10 The ends of the pipe serving as bearing pivots are adapted to be seated in the upper pair of notches 15, or in the pair of notches 16, or any of the pair of notches 16 in the event that more than one pair is provided
- 15 in the inclined front edges of the side members.

A short distance in advance of the bolt 19, the upper face of the actuating lever is provided with a depression 21, which indicates the point of the actuating lever adapted to be engaged with the axle or other member of a vehicle for the purpose of lifting the vehicle, and in advance of this depression, or "seat" as it may be termed, is a second bolt 22 passed through the actuating lever in the same manner as the bolt 19 and having a nut 23 applied to the upper projecting end of said bolt. This bolt and the bolt 19 serve to prevent splitting of the actuating lever and the nuts of the bolts also serve as stops, as will be explained hereinafter.

The retaining lever 5 is normally positioned as indicated in Fig. 1, that being the position which allows the actuating lever to be inclined downwardly from its rear end. Said retaining lever is preferably in the form of a strip of wood of suitable quality having a notched lower end 24, the shoulder 25 of which is adapted to engage either of the steps or abutments 10 of the spacing block 9. This retaining lever is substantially of the same width as the actuating lever and has secured to opposite sides thereof metallic strips 26 which project beyond the upper ends thereof and form a fork adapted to straddle or receive the outer or front end of the actuating lever, a pivot bolt 27 being passed through the upper ends 50 of said metallic strips and through said actuating lever and serving to allow the retaining lever to swing on said actuating lever with a view of permitting the lower end of said retaining lever to be moved into 55 or out of engagement with one of the steps or abutments 10 on the upright or support, the particular step or abutment engaged by the shoulder of said actuating lever, depending on the pair of notches into which the 60 bearing or fulcrum pivots of the actuating lever is seated.

Secured to the retaining lever is a screw eye 28 having one end of a wire or adjusting element or rod 29 secured thereto, said wire extending rearwardly underneath the

actuating lever and being guided in guide eyes 30 secured to the under side of said lever, the rear extremity of said wire or adjusting element being bent into loop form 70 31 to provide a suitable handle for actuating said wire or adjusting element.

Upon sliding the wire 29 lengthwise underneath the actuating lever, the retaining lever is swung on its pivot 27, thus the wire serves as a convenient 75 means of moving the notched end of said retaining lever into or out of engagement with one of the steps or abutments 10 of the upright or support.

As shown in the drawings, the bearing or 80 fulcrum pivots 18 of the actuating lever are engaged with a pair of bearing notches in the inclined front edges of the side members, and when thus positioned the retaining member is adapted to engage the lower 85 step or abutment of the upright or support. When the bearing or fulcrum pivots 18 are entered in the upper pair of bearing notches 15, the shouldered lower end of the retaining lever is adapted to be engaged 90 with the upper step or abutment 10.

From the foregoing it will be apparent that if additional pairs of bearing notches are provided, additional steps or abutments will be required; there being at all times 95 the same number of steps or abutments as there are pairs of bearing notches in the side members of the upright.

When placing the jack into use, the parts are substantially as shown in Fig. 1, with the actuating lever inclined downwardly and forwardly and the retaining lever swung forwardly out of engagement with the spacing or abutment block. By thus positioning the parts, after having determined the 100 pair of notches in the upright most suitable to receive the bearing or fulcrum pivots of the actuating lever, the jack is moved underneath the part of the vehicle adapted to be engaged, the jack being so positioned and the actuating lever 17 being arranged at an inclination that the depression or seat 21 is directly underneath the axle or other member to be engaged by the actuating lever. The rear or long end of the actuating 115 lever is then swung downwardly, causing the front end or that portion in front of the fulcrum pivots to swing upwardly, and by reason of the large leverage provided by the construction shown and described, the vehicle or a part of the vehicle is elevated by a single action of the device. Now, by drawing rearwardly on the adjusting wire 29, the retaining lever will be drawn rearwardly to bring the shoulder 25 of said lever 120 into engagement with one of the steps or abutments 10 of the upright or support and thus retain the vehicle or the lifted portion of the vehicle in elevated position.

When positioning the jack underneath an 130

axle of a vehicle, it may, in some cases, be found necessary to position the actuating lever 17 at a decided inclination, and when swinging the outer end of said lever down-
wardly to bring the depression or seat 21 of said lever against the under side of the axle and then applying sufficient pressure against said lever to raise the vehicle, the axle has a tendency to slide off the end of the lever; and when this takes place, the axle will come in contact with the nut 23 of bolt 22 and be held against further sliding movement on said lever.

When the vehicle is elevated and the outer end of the actuating lever is depressed and positioned at a decided downward inclination, as sometimes happens, jarring of the vehicle supported by the jack may cause the axle to slide rearwardly along the lever, and in that case, the nut 20 of the bolt 19 will be engaged by the axle and the latter be stopped thereby.

Having thus described my invention, what I claim is:—
1. A vehicle jack comprising a support having spaced uprights and abutments, notches in said uprights arranged in pairs, an actuating lever having fulcrum pivots removably entered in a pair of said notches and extending forwardly and rearwardly from said pivots, and a retaining lever having a forked upper end straddling said actuating lever and being pivotally connected thereto, said retaining lever having a shouldered lower end adapted to engage one of the steps or abutments of said upright.

2. A vehicle jack comprising a support formed of spaced wooden side members and

a stepped abutment between the lower portions of said side members, said side members having a portion of their front edges inclined upwardly and rearwardly, metallic strips applied to said side members along their inclined front edges, notches in the upper edges of said side members continued through said metallic strips, notches in the front inclined edges of said side members also continued through said metallic strips, an actuating lever having fulcrum pivots adapted to engage either the notches in the upper edges or in the inclined front edges of said side members, and means pivotally connected to said actuating lever adapted for engagement with the stepped abutment between said side members.

3. A vehicle jack comprising an upright, an actuating lever pivotally mounted on said upright, and means carried by said actuating lever for retaining the same in actuated position, said actuating lever having fulcrum pivots formed by a metallic tube inserted through said lever and projecting from opposite sides thereof, and a bolt passing through said lever and said tube at right angles to the latter.

4. A vehicle jack comprising an upright, an actuating lever of wood pivotally mounted in said upright, said lever having a tube extending transversely therethrough and projecting from opposite sides to serve as fulcrum pivots, a bolt passing through said lever and through said tube, and a second bolt passing through said lever in advance of said first-mentioned bolt parallel with the latter.

In testimony whereof I affix my signature.
JOSIAH S. ANDREWS.
